UNITED STATES PATENT OFFICE

110,140

DESIGN FOR A PITCHER TOP OR SIMILAR ARTICLE

Theolian Gamble, Des Moines, Iowa

Application December 14, 1937, Serial No. 73,595

Term of patent 14 years

To all whom it may concern:

Be it known that I, Theolian Gamble, a citizen of the United States, and a resident of Des Moines, in the county of Polk and State of Iowa, have invented a new, original, and ornamental Design for a Pitcher Top or Similar Article, of which the following is a specification, reference being had to the accompanying drawing, forming part thereof:

I claim:

The ornamental design for a pitcher top or similar article, substantially as shown.

THEOLIAN GAMBLE.
